UNITED STATES PATENT OFFICE.

ALEXANDER D. ELLIOTT, OF VIOLA, ILLINOIS.

CONVERTIBLE FURNITURE.

1,120,701.

Specification of Letters Patent.

Patented Dec. 15, 1914.

Application filed January 15, 1914. Serial No. 812,323.

To all whom it may concern:

Be it known that I, ALEXANDER D. ELLIOTT, a citizen of the United States, residing at Viola, in the county of Mercer and State of Illinois, have invented certain new and useful Improvements in Convertible Furniture, of which the following is a specification.

My invention relates more particularly to an article of furniture which normally forms a seat, chair or settee but which may be readily extended or opened up to form a bed or couch. For this purpose it comprises a stationary member upon which is pivoted a swinging member which may be folded up with or against the stationary member to provide the back and arms of a chair, bench or settee and which when swung into the open position furnishes a part of the support for the mattress.

In the accompanying drawing, I have shown two specifically different articles of furniture embodying my invention and in the following specification I have described the same in detail but it is to be understood that the specific disclosure is for the purpose of exemplification only and that my invention is not limited thereto but is set forth in the following claims in which I have endeavored to distinguish it from the prior art so far as known to me without, however, relinquishing or abandoning any portion thereof.

In the accompanying drawings Figure 1 shows a longitudinal vertical section of one of the preferred forms of my invention, referred to above, in open position in full lines and in closed position in dotted lines, and Fig. 2 a similar view of the other, parts however being broken away in the latter figure to more clearly disclose the construction, and the dotted lines showing an intermediate position of the parts; Fig. 3 is a plan and Fig. 4 a side elevation of a detail of that form of the invention shown in Fig. 2 and Fig. 5 is an elevation of another detail thereof to be described later.

As will be apparent from the following description the framework of the furniture embodying my invention may be made of wood and metal or all of metal as desired.

Referring first to the article of furniture shown in Fig. 1 the stationary member comprises a pair of end pieces 6, (of which, by reason of the plane of section, but one is shown in the drawing,) which are connected

to form a rigid structure by any desired number of transverse strips 7, 8 and by a round rod 9 at the lower front ends of the same which also forms the hinge or pivot 60 for the swinging member 10.

The latter is shown in elevation in the figure, the plane of section of said figure being between the same and the stationary side frame which is not shown. The pivoted member 10 comprises a rectangular frame 11 which upon one face is provided with a cushion 12 or may be otherwise finished off to furnish a back when the article is folded for use as a chair or settee, and on the other side carries the wire webbing which forms a part of the support for the hair or other mattress. This swinging member also includes a pair of bars 13 which when the furniture is in its folded condition form the arms of the chair or settee and when the article is unfolded constitute legs or supports for this portion of the bed. The sides of this swinging member may be finished off in any desired manner and as shown are designed with the spindles 14 commonly found in the sides of settees, chairs, etc., and are made more rigid by braces 15, 16, preferably of metal and connecting the members 17 with the frame 11, as shown and suitable cross-pieces connect the sides into a firm rigid structure.

The support for the hair or other mattress comprises in addition to the swinging frame 11 referred to above, a rear bodily movable frame 18 and an intermediate frame 19, each of which is rectangular in plan and provided with wire webbing. If desired the wire webbing can be continuous throughout the three frames, though preferably, for convenience in folding, the adjacent edges of the webbing on the frames are unconnected. The longitudinal members of the rear frame 18 carry at their rear ends and upon the outer faces thereof rollers 20 which engage tracks 21 formed in or attached to the side members 6 of the stationary frame. The intermediate frame 19 is pivoted to frame 18 at 22 and to frame 11 at 23 and forms the top of a rectangular boxing 24 which supports said frame when the article of furniture is extended into a bed being provided for this purpose with rollers or projections 25 at its outer lower rear corners, which are received in tracks 27 on the insides of the end frames of the stationary member. Braces 28 support the intermediate frame 19.

diate points of these tracks. It will now be seen that when the swinging member 10 is folded inward against the stationary member the boxing 24 is guided into the position shown in dotted lines and the rear end of the frame 18 is guided by the guides 21 first in an inclined direction and finally in a vertical direction until said frame comes into the position shown in dotted lines.

5 The seat 29 of the settee is provided with a depending panel 29^a and is pivoted to the swinging frame at 30 and connected by links 31 with the lower forward corners of boxing 24 so that it swings or revolves in the 10 swinging frame from the position shown in full lines to that shown in dotted lines as the swinging member is folded upon the stationary member to form a chair or settee.

In the modification shown in Figs. 2, 3, 20 4 and 5, the stationary and swinging frames are or may be substantially the same as in the modification just described and corresponding parts thereof are identified by the same numerals of reference with primes applied thereto, however. The channeled guides for the rear ends of the rear frame and for the boxing are omitted, however, and other expedients adopted for securing correct movement of said movable members.

25 For this purpose the edges 10^a of the sides of the swinging member are perpendicular at their upper portion to the mattress-supporting frame and are engaged by the adjacent longitudinal members of the boxing 24' and hold the latter level in the position shown in full lines in Fig. 2. The bodily movable frame 18' is, as in the earlier described modification, pivoted by its side members to the upper rear corners of the 30 boxing. The rear ends are supported and guided in plates 33 (see Figs. 2 and 5) attached to the rear edges of the side pieces 6' of the stationary frame, which plates are slotted at their upper edges to receive the 35 depending flanges 18^a of said frames. The flanges extend beyond the points 24^a at which they are pivoted to the boxing and are notched at their forward ends as at 18^b for the purpose of engaging studs 32 upon 40 the ends of the boxing as the swinging member is closed upon the stationary member (see dotted lines in Fig. 2). The seat 29' is connected to the boxing in the same manner as is that of the earlier-described form 45 of the invention. As the swinging member is raised to close it upon the stationary member the bodily-movable frame 18' is first thrust rearwardly by reason of the movement of the boxing and then tilted 50 upon the supports 33 until its notched ends engage the studs 32 upon the boxing. Further movement of the swinging member causes the boxing to swing about the pivots by which it is connected to the swinging 55 member so that it ultimately reaches a po-

sition similar to the closed position of the boxing 24 in the modification shown in Fig. 1. The seat 29' is pivoted at 30' in the sides of the swinging member and also connected by links 31' to the boxing whereby it is caused to follow the latter and ultimately assume the position shown in dotted lines in Fig. 1. It will thus be seen that the movement of the parts of the modification shown in Fig. 2 is very similar indeed to that of the parts of the earlier-described form of the invention and the ultimate positions both when the article is opened to form a bed and when it is closed to form a chair or settee are substantially the same in the two modifications.

I claim:

1. In an article of furniture of the class described, a stationary frame, a swinging frame pivoted thereto and adapted to form a partial support for a mattress when in open position and to fold against said stationary frame, a bodily movable frame, pivotal connections between said bodily movable frame and swinging frame, and guides engaging and adapted to raise the free end of the bodily movable frame and direct the latter into a substantially vertical position as the article is closed. 85

2. In an article of furniture of the class described, a stationary frame, a swinging frame pivoted thereto and adapted to form a partial support for a mattress when in open position and to fold against said stationary frame, a bodily movable frame, an intermediate frame pivoted between the bodily movable frame and the swinging frame and guides engaging and adapted to raise the free end of the bodily movable frame and direct the latter into a substantially vertical position as the article is closed. 100

3. In an article of furniture of the class described, a stationary frame, a swinging frame pivoted thereto and adapted to form a partial support for a mattress when in open position and to fold against the stationary frame, a bodily movable frame, an intermediate frame pivoted between the bodily movable and swinging frames, means 110 for supporting the intermediate frame and guides on the stationary frame, engaging and adapted to raise the free end of the bodily movable frame and direct the latter into a substantially vertical position when the article of furniture is closed. 115

4. In an article of furniture of the class described, a stationary frame, a swinging frame pivoted thereto and adapted to form a partial support for a mattress when in open position and to fold against the stationary frame, a bodily movable frame, guides on the stationary frame adapted to guide said bodily movable frame from the horizontal position when open to a substan- 125 130

tially vertical position when closed, an intermediate frame pivoted between the bodily movable and swinging frames, studs on the intermediate frame and guides on the stationary frame receiving the studs.

5. In an article of furniture of the class described, a stationary frame, a swinging frame pivoted thereto and adapted to form a partial support for a mattress when in open position and to fold against said stationary frame, a bodily movable frame, pivotal connections between said bodily movable frame and swinging frame, studs on the free end of the bodily movable frame and inclined guides upon the stationary frame with which said studs coöperate to direct said bodily movable frame from a horizontal position when open to a substantially vertical position when closed.

20. 6. In an article of furniture of the class described, a stationary frame, a swinging frame pivoted thereto and adapted to form a partial support for a mattress when in open position and to fold against said stationary frame, a bodily movable frame, an intermediate frame between the swinging and bodily movable frames and pivoted thereto, means on the stationary frame for supporting the intermediate frame, studs on the free end of the bodily movable frame, and inclined guides on the stationary frame coöoperating with said studs to guide the bodily movable frame from a horizontal to a substantially vertical position.

35. 7. In an article of furniture of the class described, a stationary frame, a swinging frame pivoted thereto and adapted to form a partial support for a mattress when in open position and to fold against said stationary frame, a bodily movable frame, an intermediate frame pivoted to said bodily movable and swinging frames, a seat member pivoted to the swinging frame, and connections from the seat member to the intermediate frame for swinging the former.

40. 8. In an article of furniture of the class described, a stationary frame, a swinging

frame pivoted thereto and adapted to form a partial support for a mattress when in open position and to fold against said stationary frame, a seat carried by said swinging frame, a bodily movable frame, pivotal connections between said bodily movable frame and swinging frame, and guides for the free ends of the bodily movable frame on the stationary frame adapted to guide said bodily movable frame from a horizontal to a vertical position.

45. 9. In an article of furniture of the class described, a stationary frame having a suitable base, a swinging frame pivoted to the base at the forward edge thereof and comprising a mattress-supporting section, a bodily movable frame pivotally connected to said mattress-supporting section of the swinging frame and coöperating at its free end with guides upon the stationary frame whereby said bodily movable frame is driven rearwardly by the swinging frame when the latter is closed and turned from a horizontal to a vertical position.

50. 10. In an article of furniture of the class described, a stationary frame comprising a substantially rectangular base and an upright back portion, a swinging frame pivoted to the front edge of the base and having a mattress-supporting section which is substantially horizontal when said swinging frame is open and engages the upright section of the stationary frame when in closed position, an intermediate mattress-supporting member pivoted to the swinging frame, a bodily movable mattress-supporting frame pivoted to the intermediate member at the rear edge thereof, the rear end of said bodily movable member engaging guides on the upright portion of the stationary frame whereby it is guided from a horizontal to a vertical position as the swinging member is raised.

ALEXANDER D. ELLIOTT.
